MINIATURE ACORN-TUBE SOCKET WITH
FLOATING CONTACTS

Emerick Toth, Takoma Park, Md.

Application March 27, 1947, Serial No. 737,685

6 Claims. (Cl. 173—328)

(Granted under the act of March 3, 1883, as
amended April 30, 1928; 370 O. G. 757)

1

This invention relates to electron tube support and contactor mechanisms and in particular to alignment compensating sockets for "acorn" type electron tubes.

The present trend in the design of high frequency electron tubes is toward the elimination of the customary tube base, spring type connections to the elements being made directly to the lead wires as they emerge from the metal-glass seals of the tube envelope. This type of construction permits greatly shortened leads with consequent reduction in lead inductance and shunting capacitance but does limit the amount of force that can be applied to the tube leads for fear of breaking the necessary metal-glass seals. Such a force limitation is particularly critical when handling tubes of the "acorn" type having the leads brought out in the form of stiff wires of relatively large diameter extending radially from the tube primarily in a plane perpendicular to the major axis thereof. With conventional rigidly mounted terminal contactor members, great accuracy of tube and socket manufacture is required so that the terminals will fit the contactor members exactly without placing a strain on the glass portions of the tube. With such conventional sockets, extreme care is also required when inserting or removing a tube to avoid placing excessive strains on the tube itself.

It is therefore an object of the present invention to provide a socket connector assembly for a tube of the "acorn" or other radial lead type capable of adjusting itself for reasonable misalignment of the tube terminals when the tube is in place or being inserted or removed.

Another object of the present invention is to provide a socket for a tube of the type having a plurality of terminals protruding radially therefrom in a plane perpendicular to the major axis thereof in which individual motion of the terminal contactor members is permitted in three dimensions to compensate for misalignment of the individual terminals.

Other and further objects and features of the present invention will become apparent upon a careful consideration of the following detailed description and accompanying drawings.

Fig. 1 is a plan view of a preferred type of tube socket constructed in accordance with the teachings of the present invention.

Fig. 2 is a view of a stamped terminal contactor member in an intermediate stage of construction.

Figs. 3 and 4 show different views of a typical terminal contactor member and the mounting

2

thereof in the typical socket of Fig. 1 to achieve three dimensional alignment compensation.

In accordance with the fundamental concepts of the present invention, a tube socket for an electron tube having contacts of the radial pin type is provided which is capable of adjusting itself for reasonable amounts of misalignment of the tube pins. Individual contact members, provided for each pin, are mounted in such a manner that freedom of motion of the contact members is remitted in three dimensions. As a further refinement, the contact members have highly conductive surfaces with large areas to insure low inductance.

With particular reference to Fig. 1, a socket is shown for an electron tube of the "acorn" type having a seven pin radial contact assembly. The base member of the socket is a section 10 of insulating material having preferably a cylindrical aperture 11 for receiving an end of the electron tube. In use, the section 10 is preferably secured to a metallic chassis or other support member by suitable bolts or screws fitted into holes 12, 13.

Terminal contact members 14—20 are placed in a circular orientation in cut-back portions of the base 10. These members are held in place by suitable holding pins or rivets, the heads of which are visible in the aperture 11 on the inner side of base 10 and typified by numeral 21. The holding pins preferably engage the contact members in a flexible yet secure manner to permit rotational and tilting motion thereof to compensate for minor misalignment of the tube terminals. These contact members are so mounted and constructed that in the process of inserting a tube, the members are drawn up close on the tube lead by spring action to reduce the lead length and consequently the inductance thereof.

Various views of the contact members are shown in Figs. 2, 3, 4. At one step in the process of manufacture of an individual contact member, a section having an enlarged outline as shown in Fig. 2 is obtained. This section may be obtained as by stamping from a flat sheet of metal of high conductivity and preferably having somewhat tempered or elastic characteristics. The central portion of this contact member is provided with an upper V-shaped notch 22 for receiving the tube terminal. The central portion is also provided with an elongated aperture 23 to engage the holding pins in such a manner as to permit pivotal motion of the contact members about the pin as well as motion in a plane perpendicular to the major axis of the tube terminal. The

raised portions 24, 25 located to either side of the central portion of the contact member are bent along the dotted lines to provide a resilient structure for holding the tube terminal firmly against the slot 22. The extending side portions 26, 27 provide low inductance soldering lugs for connection to the external circuits. The downwardly extending central portion 28 of the structure of Fig. 2 is bent to an angle of approximately 90 degrees with respect to the central portion to provide spring action to hold the contact member in a reference position in absence of any displacing force from a tube terminal.

The completely formed contact member is shown in a side view in Fig. 3 and in an end view in Fig. 4. In Fig. 3 the location of the tube terminal notch is indicated by numeral 22 and one of the resilient terminal holders is indicated by numeral 24. The contact member is affixed to the cross-section of a portion of the base number 10 by the pin or rivet 30. The extending portions of the contact member as indicated by numeral 26 have large surface areas to provide low inductance paths for high frequency electrical currents. In the relaxed condition, the positioning spring portion 28 holds the contact member in a reference position wherein the lower end portion of the elongated aperture 23 rests against pin 30.

In the end view of the contact member as shown in Fig. 4, a method of folding the resilient sections 24 and 25 to hold a tube terminal in place against the V-slot 22 is shown. Members 24 and 25 are bent inwardly near the ends thereof to press the tube terminal against slot 22.

From the foregoing discussion it is apparent that considerable modification of the features of the present invention is possible and while the device here shown and the form of apparatus for the operation thereof constitutes a preferred embodiment of the present invention, it is to be understood that the present invention is not limited to this precise device and form of apparatus and that changes may be made therein without departing from the scope of the invention which is defined in the appended claims.

The invention described herein may be manufactured and used by or for the Government of the United States of America for governmental purposes without the payment of any royalties thereon or therefor.

What is claimed is:

1. A socket for an electron tube of the type having a plurality of terminals protruding radially therefrom in a plane perpendicular to the major axis thereof, comprising a generally annular base member of insulating material into which the tube is adapted to extend, a plurality of radially extending grooves formed in the outer periphery of said base member and having a back formed by the inner periphery of said base member and a bottom formed by the lower face of said base member, said grooves being angularly spaced in accordance with the angular spacing of said tube terminals, a supporting tube terminal contactor for each tube terminal disposed within corresponding ones of said grooves, each of said contactors comprising an elongated central body portion extending in parallel relation to the major axis of said tube and terminating beyond the upper face of said base member in a tube terminal gripping portion for engagement with said tube terminals, a longitudinal mounting slot formed in said body portion, means engaging said slot to pivotally mount the central body of said contactors to the back of said grooves, spring

biasing means integrally formed with each of said elongated central body portions extending radially outwardly therefrom, said spring biasing means being coactive with the bottom of said grooves for holding each terminal contactor in a reference position in the absence of a displacing force from a tube terminal.

2. A contactor for pin type radio tube terminals, comprising a tri-furcated metallic body portion 10 comprising a flat elongated center arm and a pair of substantially flat, elongated parallel, side arms each lying in planes perpendicular to the plane of the center arm with the long axis of the side and center arms all parallel, the center arm of said body portion having a wedge shaped notch formed in one end thereof for receipt of a tube terminal, the corresponding end extremities of said side arms extending beyond the apex of said wedge shaped notch; and being formed with inclined portions extending toward each other immediately beyond the apex of the wedge shaped notch in said center arm whereby said inclined portions are operative to engage the tube terminal and urge the same into firm electrical contact with the apex of the notch.

3. A contactor for pin type radio tube terminals, comprising a tri-furcated metallic body portion, comprising a flat elongated center arm and a pair of substantially flat, elongated parallel, side arms 30 each lying in planes perpendicular to the plane of the center arm with the long axis of the side and center arms all parallel, the center arm of said body portion having a wedge shaped notch formed in one end thereof for receipt of a tube terminal, 35 said center arm also having an elongated aperture formed therein for receipt of a pin like mounting member, the corresponding end extremities of said side arms extending beyond the apex of said wedge shaped notch; and being formed with inclined portions extending toward each other immediately beyond the apex of the wedge shaped notch in said center arm whereby said inclined portions are operative to engage the tube terminal and urge the same into firm electrical contact 45 with the apex of the notch.

4. A contactor for pin type radio tube terminals, comprising a tri-furcated metallic body portion, comprising a flat elongated center arm and a pair of substantially flat, elongated parallel, side arms each lying in planes perpendicular to the plane of the center arm with the long axis of the side and center arms all parallel, the center arm of said body portion having a wedge shaped notch formed in one end thereof for receipt of a tube terminal, 55 the corresponding end extremities of said side arms extending beyond the apex of said wedge shaped notch; and each being bent in the shape of a V with the apex of the V extending immediately beyond the apex of the wedge shaped notch whereby said V shaped end extremities are operative to engage the tube terminal and urge the same into firm electrical contact with the apex of the notch.

5. A socket for a radio tube or the like, said socket being of annular shape and being formed with a plurality of recesses, a contact clip housed in each of said recesses and being retained in said socket by the coaction therewith of the portions of the socket bounding the recess in which it is positioned, said contact clip having a base, and contact pin receiving means forming a portion of each of said clips and adapted to receive pins extending radially from a tube positioned within said socket, said contact pin receiving means comprising three tabs extending upward from the

base of said clip in parallel directions, one of said tabs being located on the side of said clip closest to the axis of said socket and having formed in its free end a notch having its apex directed toward said base, and the remaining two tabs being resilient and having their free ends bent toward each other to form a yieldable barrier to movement of one of said contact pins into or out of said notch.

6. A socket for a radio tube or the like, said socket being of annular shape and being formed with a plurality of recesses, a contact clip housed in each of said recesses and being retained in said socket by the coaction therewith of the portions of the socket bounding the recess in which it is positioned, said clip having a base, contact pin receiving means forming a portion of each of said clips and being adapted to receive pins extending radially from a tube positioned within said socket; said contact pin receiving means comprising an element extending from said base in substantial parallelism with the axis of said socket and terminating at its free end in a notch having its apex directed toward said base, a pair of tabs extending from said base with their major surfaces lying in parallel planes normal to the plane of said notch, said tabs being resiliently

urged toward each other at their free ends to form a yieldable barrier to the movement of one of said radially extending pins into or out of said notch, and a resilient member joined to said base beneath said element and extending below and toward the opposite side of said base, said member acting between said clip and said socket to urge the notched end of said element radially inwardly of said socket to the limit of movement of 10 said clip.
